PACKAGE ASSEMBLY

James A. Baker, Shorewood, Wis., assignor to
 Milprint, Inc., Milwaukee, Wis., a corporation
 of Delaware

Application July 2, 1945, Serial No. 602,821

4 Claims. (Cl. 206—45.33)

1

The present invention relates generally to improvements in the art of packing diverse commodities in order to facilitate transportation, storage, and merchandising thereof; and relates more specifically to improvements in the construction and use of special wrapping assemblies for tapered cup-shaped or other non-rectangular prismatic containers or the like.

The primary object of my invention is to provide improved instrumentalities for effectively confining tapered circular or otherwise non-rectangular prismatic receptacles within wrappers which will produce rectangular prismatic final packages adapted to be compactly stacked or otherwise confined within rectangular spaces.

In the art of packaging commodities such as liquids, solids, or mixtures of liquids and solids, in individual batches for convenient handling, it is frequently desirable to utilize tapered cups or other non-rectangular prismatic containers. It is difficult to stack and to otherwise assemble these tapered receptacles in shipping boxes and other rectangular confining spaces, because of the fact that their peculiar shape prevents proper side wall contact between the adjacent containers sufficient to maintain the same in erect condition at all times; and the cup-like receptacles would therefore tend to tip over and roll around with resultant damage and waste of commodity. It is also impossible to utilize standard automatic wrapping machines in order to quickly and effectively wrap such non-rectangular containers into neat packages, because these machines are primarily adapted to handle rectangular prismatic bodies. When utilizing such cup-shaped commodity containers, it is also often desirable to display and to sell the batches in groups of two or more of the individual packages, and to provide attractive display wrappers for the groups. While various methods of wrapping and of confining such tapered receptacles in order to eliminate the above mentioned difficulties have heretofore been proposed, none of these have proven satisfactory either because they were too costly or because they did not solve the problem.

It is therefore a more specific object of the present invention to provide an improved package assembly for tapered cup-shaped containers or the like, whereby one or more of the individual cups may be effectively maintained in upright position and confined within a rectangular prismatic space for compact and stable stacking or other disposition.

Another specific object of the invention is to

2

provide an attractive and effective display wrapper for cup-like tapered receptacles, which may be produced at slight cost and readily applied to the commodity containers.

5 A further specific object of this invention is to provide an improved form for permitting rapid and effective wrapping of several similar relatively unstable individual commodity laden cups or the like, in compact grouped arrangement and in a highly attractive manner, with the aid of standard automatic container wrapping machines.

10 Still another specific object of my invention is to provide a new and highly useful and readily applicable combined support and wrapper for several individual commodity laden receptacles, which may be conveniently utilized to assemble the containers in successive regularly arranged groups.

15 These and other specific objects and advantages of the invention will be apparent from the following detailed description.

20 A clear conception of a preferred embodiment of the invention, and of the mode of producing package assemblies involving the present improvement, may be had by referring to the drawing accompanying and forming a part of this specification wherein like reference characters designate the same or similar parts in the various views.

25 Fig. 1 is a plan view of one of the improved cup supporting, positioning, and partial confining blanks used in producing the new package assembly;

30 Fig. 2 is a perspective view of one of the blanks of Fig. 1 folded and assembled for normal use, and showing several tapered cup-shaped commodity laden containers initially applied thereto; and

35 Fig. 3 is a similar perspective view of one of the improved final package assemblies comprising the assembled blank, a pair of commodity laden containers, and an outer transparent wrapper coacting with and enclosing the base blank and containers.

40 While the invention has been shown and described herein by way of illustration as being advantageously applicable to a package assembly having a pair of tapered commodity laden circular cups positioned side by side in a cardboard support and finally enclosed within a transparent wrapper to produce a rectangular prismatic package, it is not my desire or intent 45 to unnecessarily restrict the scope or to limit

50 55

the utility of the improvement by virtue of this illustrative disclosure.

Referring to the drawing, the improved package assembly shown therein, comprises in general a blank 5 formed of cardboard or other relatively stiff but inexpensive sheet material; a pair of similar commodity laden cup-shaped tapered containers or receptacles 6 each enclosed at the top by a sealing cover 7; and an outer wrapper 8 of any suitable relatively thin but durable sheet material.

The improved cardboard blanks 5 may be cut from sheets and properly scored with the aid of suitable punches and dies, and each of these blanks 5 consists primarily of a rectangular elongated base section 9, having rectangular wall flaps 10 hingedly secured to its opposite ends, and also having a rectangular positioning plate or deck 11 swingably associated with one side thereof by means of an intervening rectangular spacer wall 12. The flat deck 11 is of approximately the same shape and size as the base section 9, and has a pair of circular cup positioning openings 13 therein, and the side of the deck 11 remote from the hinge wall 12 is provided with another rectangular spacer wall 14 hingedly connected thereto along one edge and provided along its opposite edge with an integral attaching flap 15.

The tapered prismatic receptacles 6 may be formed of paper, metal, or other material and have lower end diameters approximately equal to those of the deck openings 13, and these cups may be filled with batches of either liquid, solid, or mixed liquid and solid commodities of various kinds. The batches may be confined within the individual commodity laden receptacles by means of covers 7 or otherwise, so as to avoid undesirable escape of material from the cups.

The wrappers 8 may be formed either of opaque or transparent sheet material, and may be provided with attractive indicia and advertising. The material from which these wrappers are formed should be rather thin and flexible but tenacious in texture, and the use of transparent sheet material is desirable for display purposes.

When producing an improved package assembly with the aid of a blank 5, receptacles 6, and an outer wrapper 8 such as described herein, the blank 5 should first be assembled as shown in Fig. 2 by folding the spacer walls 12, 14 relative to the positioning deck 11 so as to bring this deck above and parallel to the base section 9, and by thereafter gluing the flap 15 to the side edge of the base remote from the spacer wall 12. The commodity laden tapered cup-shaped receptacles 6 may then be positioned with their lower ends within the deck openings 13 and resting upon the base section 9 of the blank 5. The end walls or flaps 10 may then be swung into erect position into contact with the adjacent ends of the deck 11 and with the adjacent closure caps or covers 7 of the cups, whereupon the outer wrapper 8 may be readily applied and adhesively attached to the upright end wall flaps 10 as shown in Fig. 3 to produce a rectangular prismatic final package.

Because of the fact that the rigid base section 9 and deck 11 cooperate with the stiff end walls or flaps 10 and with the spacer walls 12, 14 to provide a relatively rigid rectangular prismatic form for confining the tapered cups 6, these cup and form assemblages may be readily finally wrapped in most of the standard wrapping machines now in common use. This is an exceedingly important feature of my present invention, since it permits rapid and convenient final wrap-

ping of many types of bodies and receptacles for diverse commodities, which could heretofore be wrapped only by slow and tedious methods and at considerably higher cost.

When the composite package has been thus properly assembled, the lower ends of the receptacles 6 will be definitely positioned and held in proper position by the deck 11; and the upper rims of the cups will be snugly engaged by the side wall flaps 10, and will also contact each other at the central transverse vertical plane of the package. The base section 9, flaps 10, and the spacer walls 12, 14 will then cooperate with the upper cup rims and covers 7, to provide the open sided rigid form for the wrapper 8, since the flaps 10 are of the same length as the height of the receptacles 6, and are also of the same width as the diameters of the upper cup rims. The wrapper 8 when properly applied to this form produced by the assembled blank 5 and cups 6, will obviously provide a well supported rectangular prismatic enclosure for the receptacles and a final package assembly which may be readily grouped in compact arrangement with other similar assemblages. By utilizing transparent wrappers 8, the packed containers 6 will also be plainly visible for display and merchandising purposes, and both the cups and the wrappers, as well as the blanks 5, may be decorated so as to enhance the aesthetic appearance of the final packages.

From the foregoing detailed description it will be apparent that my present invention provides an improved package assembly for tapered cup-shaped receptacles 6 or the like, which is simple, compact, and durable in construction, and wherein the tapered and relatively unstable cups are effectively held in upright position and confined in a sturdy rectangular prismatic enclosure or wrapper 8. The improved final packages may be rapidly and effectively produced in standard automatic wrapping machines and besides being highly attractive in appearance, may be stacked and assembled in ordinary rectangular shipping boxes; and any desired number of the individual containers 6 may be confined in each package assembly. The blanks 5 may obviously be produced at moderate cost from inexpensive cardboard or the like, and can be quickly and conveniently assembled to produce the U-shaped rectangular forms and to also produce sockets for firmly supporting the cups, and the tapered receptacles 6 may be either commodity laden containers or any other tapered or unstable objects having generally similar shape. It is also noteworthy that the use of transparent wrappers 8 while not being essential, makes it possible to attractively display the enwrapped articles for merchandising purposes, without subjecting the receptacles 6 to direct handling, thus making the package sanitary in use by thoroughly protecting the individual containers.

It should be understood that it is not desired to limit this invention to the exact details of construction, or to the precise mode of use, herein shown and described, for various modifications within the scope of the appended claims, may occur to persons skilled in the art.

I claim:

1. A package assembly comprising, a unitary cardboard blank having a base provided with hingedly connected opposite end walls and with a deck swingably connected to the base by a spacer wall of considerably less height than said end walls, said deck having receptacle positioning

openings therein and said blank being foldable along the opposite edges of said spacer wall to position said deck a definite distance above said base and said end walls being foldable upwardly into engagement with the opposite ends of the deck to cause the end walls to project a considerable distance above the deck, receptacles having their lower ends resting directly upon said base and their upper ends flush with the tops of said end walls and being snugly confined within said deck openings, and a wrapper coacting with said base and outer sides and tops of said end walls and with the upper ends of said receptacles.

2. A package assembly comprising, a unitary cardboard blank having a base provided with hingedly connected opposite end walls and with a deck having one edge hingedly connected to the adjacent edge of said base by a spacer wall and provided along its opposite edge with a spacer flap, said deck having therein receptacle positioning openings and said blank being foldable to cause said spacer wall and flap to position said deck a definite distance above said base and said end walls being thereafter foldable upwardly against the opposite ends of the deck, receptacles having their lower ends resting directly upon said base and confined within said deck openings while their upper ends lie substantially flush with the upper edges of said walls, and a transparent wrapper coacting with said base and walls and with the tops of said receptacles to provide a prismatic enclosure for the receptacles.

3. A package assembly comprising, a one-piece cardboard blank having a rectangular base provided with hingedly connected opposite rectangular end walls and also provided with a rectangular deck swingably connected to said base by a spacer wall and having circular receptacle positioning openings therein, said blank being foldable into U-shaped formation with said walls extending upwardly from said base and said deck being foldably connected to said base by said spacer wall for disposition a definite distance above the base between the end walls, tapered cir-

cular receptacles having their lower smaller ends resting upon said base and snugly confined within said openings, and a wrapper coacting with said base and walls and with the tops of said receptacles to provide a rectangular prismatic enclosure for the latter.

4. A package assembly comprising, a one-piece cardboard blank having a rectangular base provided with hingedly connected opposite rectangular end walls and also provided with a rectangular deck swingably connected to said base by a spacer wall and having circular receptacle positioning openings therein, said blank being foldable into U-shaped formation with said walls extending upwardly from said base and said deck being foldably connected to said base by said spacer wall for disposition a definite distance above the base between the end walls, tapered circular receptacles having their lower smaller ends resting upon said base and snugly confined within said openings and also having upper enlarged ends lying in the common horizontal plane of the upper wall extremities, and a transparent wrapper coacting with said base and walls and with said enlarged upper receptacle ends to provide a rectangular prismatic enclosure for said receptacles.
